(57) **CLAIM**

I claim the ornamental design for a luggage, as shown and described.

DESCRIPTION

FIG. 1 is a perspective view of the luggage opened.

FIG. 2 is a perspective view of the luggage.

FIG. 3 is a perspective view of the luggage.

FIG. 4 is a perspective view of the luggage.

FIG. 5 is the front view of the luggage.

FIG. 6 is a back view of the luggage.

FIG. 7 is a side view of the luggage.

FIG. 8 is a side view of the luggage.

FIG. 9 is a top view of the luggage; and,

FIG. 10 is bottom view of the luggage.

The broken lines illustrate portions of the luggage and form no part of the claimed design.
